UNITED STATES PATENT OFFICE

124,228

DESIGN FOR A FAUCET

Richard T. Cornelius, Minneapolis, Minn.

Application July 3, 1940, Serial No. 93,401

Term of patent 14 years

To all whom it may concern:

Be it known that I, Richard T. Cornelius, a citizen of the United States, residing at Minneapolis, in the county of Hennepin and State of Minnesota, have invented a new, original, and ornamental Design for a Faucet, of which the following is a specification, reference being had to the accompanying drawing, forming part thereof.

In the drawing the figure is a perspective view of a faucet, showing my new design.

The other side of the faucet is substantially like the side shown in the figure.

I claim:

The ornamental design for a faucet, as shown and described.

RICHARD T. CORNELIUS.
